(73) Assignee: **Schlumberger Technology Corporation**, Sugar Land, TX (US)

(57) CLAIM

(**) Term: **14 Years**

The ornamental design for a roadway trailer for a coiled tubing reel, as shown and described.

(21) Appl. No.: **29/115,061**

DESCRIPTION

(22) Filed: **Dec. 7, 1999**

FIG. 1 is a left side elevational view of a roadway trailer for a coiled tubing reel showing our new design, the broken lines are shown for illustrative purposes only and form no part of the claimed design;

(51) LOC (7) Cl. **12-10**

FIG. 2 is a side elevational view of the right side of the roadway trailer shown in FIG. 1;

(52) U.S. Cl. **D12/101**

FIG. 3 is a top plan view of the roadway trailer shown in FIGS. 1 and 2;

(58) Field of Search **D12/101; 280/43.18,**

FIG. 4 is a front elevational view of the roadway trailer shown in FIGS. 1-3; and,

280/43.23, 788, 789; 414/474, 476, 484,

FIG. 5 is a rear elevational view of the roadway trailer shown in FIGS. 1-4.

5,887,880 * 3/1999 Mullican et al. 280/43.18

The size, shape, and position of the openings shown in the drawings are not essential to the invention.
